United States Patent Office

Des. 203,546
Patented Jan. 25, 1966

203,546

BUFFET

Bert J. Klein and Andre Bus, Altavista, and John B. Thorn, Lynchburg, Va., assignors to The Lane Company, Inc., Altavista, Va., a corporation of Virginia

Filed Apr. 19, 1965, Ser. No. 84,871

Term of patent 14 years

(Cl. D33—13)

The end of the article not shown is like the end shown while the back of the article is plain and unornamented.

We claim:

The ornamental design for a buffet, as shown and described.
